UNITED STATES PATENT OFFICE.

HARRY CRAIGHILL BADDER, OF LIVERPOOL, ENGLAND.

CONSTRUCTION OF DOORS, PANELINGS, OR THE LIKE.

968,108.

Specification of Letters Patent. Patented Aug. 23, 1910.

Application filed September 4, 1909. Serial No. 516,183.

To all whom it may concern:

Be it known that I, HARRY CRAIGHILL BADDER, a subject of the King of Great Britain, and resident of Liverpool, England, 5 have invented certain new and useful Improvements in Doors, of which the following is a specification.

This invention relates to improvements in the construction of doors, panelings, or the 10 like, of that type in which the framework or structure is built up of metal whether of assembled channel sections, or corrugated sheet metal, the interstices in the structure being filled in with refractory material or 15 cement.

The particular features of the present invention consist in constructing the framework of the door, paneling or the like, of a light multi-cellular character formed by a 20 series of metal bands or strips separated by distance pieces and secured together by bolts, screws, or rods passing through the strips. Or the cellular character of the framework may be obtained by the use of 25 corrugated sheet metal. The interstices in the framework may be afterward filled in with asbestos cement, the framework being finally inclosed with sheet metal or asbestos boards.

30 The invention is illustrated in the accompanying drawings which show the application of the invention to the construction of doors, or other fittings.

Figure 1. is an elevation partly broken 35 away to show the interior cellular construction of a door made up of metal strips in accordance with this invention. Fig. 2. is a fragmentary vertical section on the line A—A of Fig. 1., and Fig. 3. is a plan in 40 section on the line B—B of Fig. 1. Fig. 4. is an enlarged detail of a portion of Fig. 2. showing a section through the top horizontal rail and a method of attaching the panel. Fig. 5. being an analogous detail of a part 45 of Fig. 3. Figs. 6. and 7. are respectively a front elevation and sectional plan on the line C—C of Fig. 6. showing a modified form of the invention, the cellular construction 50 of the door being attained by the use of curved corrugated sheet metal. Fig. 8. is an analogous view to Fig. 7, but with angular corrugated metal. Figs. 9. and 10. show further forms of corrugated metal construction, Fig. 10. being a sectional plan on 55 the line D—D of Fig. 9.

In the form illustrated in Figs. 1. to 5.

inclusive, the horizontal rails and vertical door frame stiles 1. and 2. are built up of a series of thin metal bands or strips 3, preferably arranged vertically as shown, the 60 inner and outer strips 4 of the vertical stiles being of heavier gage metal than the remaining strips. The strips are placed edge-wise with reference to the thickness of the door and are held or spaced apart by distance pieces 5 fitted between the strips, these distance pieces being of any suitable section but preferably of tubular or hollow rectangular section as indicated in Fig. 4. The strips and distance pieces are then secured 70 together by bolts or screws 6 or they may be riveted. If screwed, an additional strip 7 may be brazed or otherwise attached along the interior of the outer strip 4 to provide more metal for the threaded end 6^a of the 75 securing bolt which is screwed therein. A recess 8 is left in the stile to receive the lock.

The stiles and rails after being made in the way described so as to form a cellular structure are filled in if desired with asbestos cement, mineral wool, or other filling, and then inclosed by a sheet metal outer casing 9, the inner ends or flanges 9^a of the casing being brought together centrally, as indicated more clearly in Fig. 4., so that they 80 may be caused to envelop the edges of the metal panel 10 to which they are riveted at 11. The fastening of the flanges 9^a to the panels 10 is hidden by the sheet metal moldings 12 which are brazed or otherwise joined 85 at 12^a to the panels and stiles. Fancy embossed sheet metal fittings may be placed over the miter junctions 13 of the moldings, and in lieu of covering the stiles and rails 1 and 2 with a sheet metal casing as described 90 they may be covered with asbestos boards fitted in the same way as the sheet metal.

In the modifications shown in Figs. 6 to 10 inclusive, the cellular framework of the vertical stiles 1 is obtained by constructing them from lengths of corrugated metal 14 the corrugations running lengthwise, the horizontal rails being similarly constructed of corrugated metal 15 but with the corrugations running transversely to the length 100 of the rail. The corrugations of the vertical and horizontal lengths of metal fit in together at the corners of the frame and the metal at these points may be permanently fastened together and the corrugated lengths 105 if desired be reinforced by screws or bolts passing through the corrugations in a similar 110

fashion to the bolts 6 of the previous modification. A sheet metal cellular structure is thus obtained and may be filled in with asbestos cement mineral wool or other filling 5 and is then inclosed by a casing of sheet metal 9 as before described and connected to the paneling.

Doors, partitions, or the like, constructed in the way described if left plain may be 10 afterward painted to imitate wood, or they may be rendered very ornate in appearance by forming the outer casing of embossed sheet metal. They also offer many practical 15 advantages as they are very light, cannot shrink or split, and are not liable to warp, and being constructed entirely of metal and asbestos cement or boards they are extremely 20 fire-resisting, the filling of asbestos cement, mineral wool, or the like, tending further to give the door great sound deadening qualities.

I claim:

1. A framed metallic door or paneled structure comprising a rail and stile framework 25 of sheet metal construction inclosing tubular distance pieces, a sheet metal casing inclosing the framework, and metal panels secured to said casing.

2. A framed metallic door or paneled 30 structure the rail and stile framework of which is built up of metal bands or strips assembled edgewise relatively to the thick-

ness of the frame, tubular distance pieces separating said strips and securing bolts passing through the distance pieces and 35 strips.

3. A framed metallic door or paneled structure the rail and stile framework of which is built up of metal bands or strips assembled edgewise relatively to the thickness 40 of the frame, tubular distance pieces separating said strips, the multi-cellular structure thus obtained being filled in with refractory cement and inclosed in a sheet-metal outer casing.

4. A framed metallic door or paneled structure comprising: a rail and stile framework built up of metal bands or strips assembled edgewise relatively to the thickness 45 of the frame, tubular distance pieces separating said strips, securing bolts passing through the distance pieces and strips, a filling of refractory cement in the interstices of the rails and stiles, a sheet metal outer casing inclosing said rail and stile framework, panels secured to said outer casing, and sheet metal moldings covering the junction of the panels and the outer casing.

In witness whereof I have hereunto set my hand in presence of two witnesses.

HARRY CRAIGHILL BADDER.
